[57] **ABSTRACT**

A method of producing FDNE using readily available fluoroolefins as a fluorine source.

5 Claims, No Drawings

A statutory invention registration is not a patent. It has the defensive attributes of a patent but does not have the enforceable attributes of a patent. No article or advertisement or the like may use the term patent, or any term suggestive of a patent, when referring to a statutory invention registration. For more specific information on the rights associated with a statutory invention registration see 35 U.S.C. 157.

**METHOD OF MAKING
FLUORODINITROETHANOL (FDNE)**

BACKGROUND OF THE INVENTION

1. Field of Invention

This invention relates to a low cost method of making fluorodinitroethanol (FDNE) which is used as a plasticizer and binder in propellants and explosives.

2. Description of Prior Art

Two methods have been used previously for manufacturing fluorodinitroethanol and both have significant difficulties. One was based on the fluorination of nitroform and the other on the fluorination of 2,2-dinitropropanediol (A-diol). Nitroform was available at low cost from Sweden until the supply was curtailed by a plant explosion in the 1970's. Environmental and safety problems still inhibit resumption of the large-scale production of nitroform. In the alternate process, A-diol was deformed with base and the salt fluorinated. This aqueous fluorination process was complicated by the formation of large amounts of insoluble sodium fluoride, the expense of the A-diol and difficulty in purifying the product. Both of these processes require elemental fluorine, with attendant high plant capital costs.

SUMMARY OF THE INVENTION

In the new process, readily available fluoroolefins are used as the fluorine source for FDNE. Nitration of 1,2-dichlorodifluoroethylene gives chlorofluoronitroacetic acid, and reaction of the latter with red fuming nitric acid gives chlorofluoronitronitrosomethane. Oxidation of chlorofluoronitronitrosomethane gives chlorofluorodinitromethane (CFDNM), and CFDNM is reduced in the presence of formaldehyde to give FDNE. These reactions are summarized below and the preliminary yields are given in Table I.

TABLE I

YIELDS OF REACTIONS LEADING TO FDNE

STEP	STARTING MATERIAL	PRODUCT	YIELD
1.	$\text{CIFC}=\text{CFCI}$	$\text{CIFCNO}_2\text{COOH}$	77%
2.	$\text{CIFCNO}_2\text{COOH}$	CIFCNO_2NO	52%
3.	CIFCNO_2NO	$\text{CIFC}(\text{NO}_2)_2$ (CFDNM)	62%
4.	$\text{CIFC}(\text{NO}_2)_2$	$\text{FC}(\text{NO}_2)_2\text{CH}_2\text{OH}$ (FDNE)	71%

**DETAILED DESCRIPTION OF THE
INVENTION**

1,2-dichlorodifluoroethylene can be purchased commercially or can be prepared in 80% yield from commercially available 1,2-difluorotetrachloroethane by zinc mediated reduction, as taught by E. G. Locke, et al., *J. Am. Chem. Society* 1934, 56, 1726. The olefin from

these sources was found to be an equal mixture of cis and trans isomers of 1,2-difluorotetrachloroethane, contaminated by 10% of 1,1-difluorodichloroethylene. The source of the unsymmetrical isomer was found to be a 10% impurity of 1,1-difluorotetrachloroethane in the 1,2-difluorotetrachloroethane used as the starting material.

The results of the nitration reaction of the 1,2-dichlorodifluoroethylene with various solutions is shown in Table II below. A first solution of 99% nitric acid and 95% sulfuric acid yielded 34% chlorofluoronitroacetic acid.

The yield of chlorofluoronitroacetic acid in the nitration reaction was increased to 44% by replacing sulfuric acid with oleum. When a mixture of oleum, nitric acid and trifluoracetic acid was reacted with 1,2-dichlorodifluoroethylene, chlorofluoronitroacetic acid was obtained in 63% yield along with 14% of the 1,2-addition product, 1,2-dichloro-1,2-difluoro-2-nitroethyl trifluoroacetate, bringing the total yield of the nitration reaction to 77%. Apparently the 1,2-addition product was formed first and then was hydrolyzed in situ, to give the acetic acid derivative. The lower boiling point and diminished water sensitivity of the 1,2-addition product makes it a potentially attractive alternative to chlorofluoronitroacetic acid in subsequent nitration reactions.

TABLE II

CHLOROFLUORONITROACETIC ACID	
Solvent	Yield
1. 95% H_2SO_4 100% HNO_3	34%
2. 30% Oleum 100% HNO_3	44%
3. 30% Oleum, CF_3COOH 100% HNO_3	63%
4. 95% H_2SO_4 , CF_3COOH 100% HNO_3 , CH_2Cl_2	50%
5. $(\text{CF}_3\text{CO})_2\text{O}$, CH_2Cl_2 , 100% HNO_3	60%

The chlorofluoronitroacetic is next reacted with fuming nitric acid. When the reaction takes place at 80° C. in 90% nitric acid containing 20% N_2O_4 , chlorofluoronitronitrosomethane is isolated in 51% yield as an intensely blue liquid by distillation. This intermediate is stable for several days at ambient temperature, but is generally used directly in the next step without further isolation or purification.

Oxidation of chlorofluoronitronitrosomethane with 30% hydrogen peroxide in nitric acid at ambient temperature gave chlorofluorodinitromethane in 62% isolated yield. The reaction was 90% complete after 15 minutes as shown in Table III.

TABLE III

TIME, MIN	OXIDATION OF CHLOROFLUORONITRONITROSOMETHANE TO CFDNM	
	$\text{CIFC}(\text{NO}_2)_2\text{NO}$ %	$\text{CIFC}(\text{NO}_2)_2$ %
0	100	0
15	10.8	56.7
30	8.2	61.7
45	5.1	60.

Chlorofluorodinitromethane can also be prepared by the direct aqueous fluorination of potassium chlorodinitromethane or by the reaction of chlorofluoronitroacetic acid with xenon difluoride.

FDNE has been prepared by reduction of fluorotrinitromethane with sodium hydroxide and hydrogen peroxide in the presence of formaldehyde. Attempted reduction of CFDNM under these conditions resulted in substantial hydrolysis to fluoride ion and the formation of small amounts of chlorofluoronitroethanol. Only trace amounts of FDNE were produced in aqueous or aqueous alcohol solvents. However, yields of FDNE as high as 71% were realized when KI was used as the reducing agent. Results using a 30% aqueous ethanolic solution of CFDNM (1 eq), KI (2.3 eq) and 30% formaldehyde solution (1.3 eq) at 70° C. are summarized in the Table IV. Formation of both FDNE and chlorofluoronitroethanol (CFNE) was observed with the maximum amount of FDNE observed at 1 h reaction time.

TABLE IV

REACTION OF CHLOROFLUORODINITROMETHANE (CFDNM) WITH KI/CH₂O

Time at 70° C. min	CFDNM %	FDNE %	CFNE %	F %
0	100	—	—	—
30	9.0	56.5	18.8	1.8
60	4.7	66.6	23.8	2.8
90	3.6	63.1	24.8	4.9
120	3.0	60.2	25.7	4.9

The effect of reaction variables on the yield of the reductive dehalogenation of CFDNM are summarized in Table V, where ¹⁹F NMR is atomic weight 19 fluoride nuclear magnetic resonance. The reaction with KI was found to be slow at room temperature (RT), with less than 10% of the CFDNM reduced after 3 hours. Reactions conducted at 40° to 75° C. for short periods and then for several days as room temperature gave the best results. When the reaction temperature exceeded 75° C., no FDNE was formed and complete hydrolysis to fluoride ion occurred.

Small amounts of chlorofluoronitroethanol (CFNE) were observed as a byproduct in most of the KI reductions. The boiling point of CFNE (40° C./0.4 mm) is closed to that of FDNE (41° C./0.1 mm) and these materials could not be separated readily by distillation.

Pure chlorofluoronitroethanol was prepared for use as a reference standard by chlorination of 2-fluoro-2-nitro-1,3-propanediol in 45% yield. CFNE was also prepared in small yield by decarboxylation of chlorofluoronitroacetic acid in aqueous formaldehyde.

Reactions of CFDNM with various "soft" nucleophiles and reducing agents are summarized in Table VI below. The best results were obtained with sodium sulfide and sodium thiosulfate. However, sodium sulfide also reacted with formaldehyde to give insoluble tri-thiane. At room temperature, even after 16 h, these reactions were not complete. The reaction mixture containing sodium thiosulfate gave two phases after it was heated at 70° C. for 10 h. The aqueous phase showed only FDNE and the organic phase showed several unidentified products in addition to FDNE.

Experimental

IR spectra were recorded in CH₂Cl₂ on a Perkin-Elmer 700 spectrometer. ¹H, ¹³C and ¹⁹F NMR spectra were recorded in CDCl₃ on a Brucker AC200 spectrometer and are reported in ppm relative to TMS and FCCl₃. Warning: Fluorodinitroethanol is a powerful skin irritant.

Chlorofluoronitroacetic Acid, Sulfuric Acid Procedure. A solution of 100% HNO₃ (30 mL) in conc. H₂SO₄ (35 mL) was added over 30 min to neat 1,2-

dichlorodifluoroethylene (48 g, 0.35 mol) at 10°–15° C.; an exothermic reaction was observed. The mixture was stirred for 10 min at 10° C. The organic layer was separated, and distilled to give 14 g (34%) of chlorofluoroni-
troacetic acid, bp 45°–65° C. (0.5 mm) (Lit² bp 90° C./8 mm): ¹⁹F NMR (CDCl₃) δ –89.71; ¹³C NMR δ 113.69 (d, J=303 Hz), 161.21 (d, J=29 Hz).

**Chlorofluoroni-
troacetic Acid, Oleum Procedure.** A solution of 100% nitric acid (9 mL) in 30% oleum (11 mL) was added over 25 min to 1,2-dichlorodifluoroethylene (13.3 g, 0.1 mol) at 14°–17° C. The mixture was stirred for 30 min at 10°–14° C. The organic layer was separated, and distilled to give 6.84 g (44%) of chlorofluoroni-
troacetic acid, bp 80°–85° C. (8 mm), identical to the material prepared above.

**Chlorofluoroni-
troacetic Acid, Oleum-Trifluoroacetic Acid Procedure.** A solution of 100% nitric acid (5 mL) and trifluoroacetic acid (4.2 mL, 54 mmol) in 30% oleum (6 mL) was added over 25 min to 1,2-dichlorodifluoroethylene (7.5 g, 56 mmol) at 10°–15° C. The mixture was stirred for 60 min at 10°–14° C. The organic layer was separated, and fractionally distilled to give 2.1 g (14.5%) of 1,2-dichloro-1,2-disfluoro-1-nitroethyl trifluoroacetate, as a 50:50 mixture of diasterimers, bp 48°–50° C. (0.5 mm): ¹⁹F NMR (CDCl₃) δ –76.27 (s, 6 F), –77.50 (s, 1 F), –78.49 (s, 1 F), –94.37 (s, 1 F), –95.30 (s, 1 F). The second fraction contained 4.0 g of chlorofluoroni-
troacetic acid, bp 55°–65° C. (0.5 mm), identical to the authentic material prepared above. The oleum layer was heated to 80° C. under vacuum (0.5 mm) to give an additional 1.61 g (63% combined yield) of chlorofluoroni-
troacetic acid.

**Chlorofluoroni-
tronitrosomethane.** Red fuming HNO₃ (7 mL) was added to a mixture of chlorofluoroni-
troacetic acid (2.4 g 15.3 mmol) and water (2 mL). The mixture was heated to 100° C. and the distillate boiling at 45°–92° C. was collected until the reaction mixture ceased to be blue in color. The blue distillate contained a mixture of N₂O₄ and 1.1 g (51%) of chlorofluoroni-
tronitrosomethane (assayed by ¹⁹F NMR using trifluorotoluene as the internal standard.) ¹⁹F NMR (CDCl₃) –85.8 (t, J=10 Hz) (Lit⁷ –85.6).

**Chlorofluorodinitromethane from chlorofluoroni-
tronitrosomethane.** A solution of chlorofluoroni-
tronitrosomethane (3.8 mg, 0.027 mmol) in 0.5 mL of CDCl₃ in an NMR tube was cooled to 5° C. and 0.2 mL of 100% HNO₃ and 0.1 mL of 30% H₂O₂ solution were added. The temperature was kept at 5° C. until the exothermic reaction subsided. The solution was then shaken at room temperature for 0.5 h until the blue color disappeared. The residue contained 2.5 mg (62% yield) of chlorofluorodinitromethane by ¹⁹F NMR anal-

ysis (trifluorotoluene internal standard). This material was identical to authentic chlorofluorodinitromethane prepared above.

Fluorodinitroethanol from chlorofluorodinitromethane. A solution of chlorofluorodinitromethane (0.95 g, 6.0 mmol), KI (2.5 g, 15 mol), and 37% aqueous formaldehyde (0.6 mL, 7 mmol) in 30% aqueous ethanol (10 mL) was heated at 70° C. for 1 h. The solution was cooled and was found to contain 0.62 g (67%) of fluorodinitroethanol and 0.19 g (23%) of chlorofluorodinitroethanol by ¹⁹F NMR assay (trifluoroethanol internal standard).

Chlorofluorodinitroethanol. A solution of 2-fluoro-2-nitro-1,3-propanediol (3.0 g, 21.6 mol) in of 12.5% bleach (NaClO, 100 mL) was stirred at ambient temperature for 3 h and then extracted with methylene chloride (2×100 mL). The combined organic solutions were dried (MgSO₄) and filtered through a pad of silica gel, and evaporated to give a yellow oil. The residual oil was distilled to give 1.3 g (42%) of chlorofluorodinitroethanol, bp 39°–40° C. (0.4 mm): ¹H NMR (CDCl₃) δ 3.58 (b, 1H), 4.16–4.49 (m, 2H); ¹³C NMR (CDCl₃) δ 662.69 (d, J=23.7 Hz), 119.97 (d, J=293.2 Hz); ¹⁹F NMR (CDCl₃) δ 98.19 (dd, J=6.8, 22 Hz). Anal. Calcd for C₂H₃ClFNO₃: C, 16.75; H, 2.11; N, 9.76. Found: C, 16.72; H, 2.37; N, 9.68.

We claim:

1. A method of producing fluorodinitroethanol (FDNE) comprising the steps of:
  - Reacting 1,2-dichlorodifluoroethylene with a mixture containing a nitrate to obtain chlorofluoroni-
troacetic acid;
  - reacting said chlorofluoroni-
troacetic acid with nitric acid to obtain chlorofluoroni-
tronitrosomethane;
  - oxidizing the said chlorofluoroni-
tronitrosomethane to obtain chlorofluorodinitromethane (CFDNM); and
  - reducing said CFDNM in the presence of formaldehyde to produce FDNE.
2. The process of claim 1 in which the initial reaction of 1,2-dichlorodifluoroethylene is with a mixture of oleum, nitric acid and trifluoroacetic acid.
3. The process of claim 2 in which said chlorofluoroni-
tronitrosomethane is oxidized with about 30% hydrogen peroxide in nitric acid.
4. The process of claim 3 in which said CFDNM is reduced with KI as the reducing agent.
5. The process of claim 3 in which KI/CH₂O in aqueous EtOH is used as the reducing agent for 2 hours at 40° C. and then 2 days at room temperature.
